UNITED STATES PATENT OFFICE.

KEN E. ROCHEL, OF GALVESTON, TEXAS.

COAL-TRANSFERRING APPARATUS.

1,204,594.

Specification of Letters Patent. Patented Nov. 14, 1916.

Application filed July 19, 1915. Serial No. 40,677.

To all whom it may concern:

Be it known that I, KEN E. ROCHEL, citizen of the United States, residing at Galveston, in the county of Galveston and State of Texas, have invented certain new and useful Improvements in Coal-Transferring Apparatus, of which the following is a specification.

This invention relates to loading and unloading, and more particularly to an improved device or apparatus designed for the purpose of transferring coal from one vessel to another, at sea, or from a yard to a vessel, at dock.

An object of the invention is to provide an arrangement of cables and pulleys whereby buckets may be simultaneously and oppositely moved to facilitate loading and unloading.

A further object of the invention is to provide a track or cable for the traveling buckets in which movement of one vessel relatively to the other may take place without slackening the cable or in any way impeding the operation of the device.

A still further object of the invention is to provide an improved means for automatically dumping the loaded or filled buckets through lowering movement thereof.

The above and additional objects are accomplished by such means as are illustrated in their preferred embodiment in the accompanying drawings, described in the following specification and then more particularly pointed out in the claim which is appended hereto and forms a part of this application.

In describing my invention in detail reference will be had to the accompanying drawings wherein like characters denote like or corresponding parts throughout the several views, and in which:—

Figure 1 is a side elevation of my improved coal transferring device or apparatus; and Fig. 2 is a top plan view of the device or apparatus as illustrated in Fig. 1.

Before proceeding with a description of the drawings I desire to call particular attention to the fact that while I have evolved my invention with reference to its use as a means for transferring coal from one vessel to another at sea, the same may be, if desired, used as a means for transferring merchandise generally, either from one vessel to another, or from one place to another as occasion may demand.

Referring now to the drawings by numerals, 1 designates the deck of a vessel from which coal is taken and 2 the deck of a second vessel onto which the coal is to be transferred. Vessels, during the transfer of coal, are adapted to be placed side by side. The mast of each vessel (the masts being designated respectively 3 and 4), is equipped with a yard arm 5 from the terminals of which pulleys 6 are hung to depend. A supporting cable or track 7 is arranged over the pulleys 6 at one end of the respective yard arms, one end of each supporting cable thus arranged, being secured to the deck of the vessel 1 and at the opposite end to the deck of the vessel 2. A spring 8 is preferably used as a fastening means whereby the terminals of the cables 7 are fastened to the deck of each vessel that one vessel may move relatively to the other without causing the supporting cable to snap or break and permitting the said cable to be taut during such relative movement.

Pulleys 9 are fastened to the yard arm 5 of the mast 4 adjacent the ends of the said arm to act as a guide means for a suitable cable 10 arranged thereover. Said cable 10 at one end is fastened to a traveling pulley 11 supported by the cable 7 while the opposite end of the cable 10 is secured to a traveling pulley 12 hung to depend from the other of the said supporting cables 7. By this arrangement, one of the traveling pulleys is caused to move oppositely and at all times in a counter direction to the other of the said traveling pulleys.

An eye 13 is made a part of each traveling pulley to act as a guide means for the operating cables 14 associated with each traveling pulley. The operating cable 14 associated with the traveling pulley 11 is fastened at one end to a bucket 15 and the operating cable 14 associated with the traveling pulley 12 fastened at one end to a bucket 16.

Drums designated respectively 17 and 18 are mounted to operate upon the deck of the vessel 1, each drum having the opposite end of its associated operating cable 14 fastened thereto.

A trip or dump cable 19 is fastened to the bottom of each bucket and to its associate traveling pulley that the said bucket may be automatically dumped or inverted when gravitated as shown to advantage in Fig. 1. Rollers 20 are fastened to the bot-

tom of each bucket to facilitate movement when filled and when moved from place to place while unsupported by cables or the like.

5 In operation, and assuming that coal is to be transferred from the deck of the vessel 1 to the deck of the vessel 2, it will be but necessary to fasten the supporting cable 7 to the yard arm terminals in the manner 10 shown to advantage in Fig. 2. As suggested, each supporting cable carries a traveling pulley 11, from which pulley a bucket is hung to depend. Support means for the respective buckets will engage the operating 15 cable 14 connected thereto. By winding the cable 14 upon the drum 17 it is evident that the said cable will be drawn taut, the bucket 15 righted and elevated sufficiently to bring enlargement 21 of said cable in contact with 20 the eye 18 of the traveling pulley 11. When thus contacted, continued winding of the cable 14 on said drum will cause the bucket 15 to move with the traveling pulley 11 along the supporting cable 7 until in a 25 position directly above the deck 1 in which event the said bucket will be lowered and later filled with the coal to be transferred. Movement of the traveling pulley 11 in the manner stated will cause the bucket 16 (said 30 bucket having been filled with coal) to travel along the supporting cable 7 in the opposite direction from that of the bucket 15 or to a position directly over the deck of the vessel 2, at which point it may be 35 lowered. The lowering movement of the bucket thus filled will cause the trip cable to be drawn taut and as the operating cable associated therewith is loose, the bucket will be inverted and the contents dumped in an 40 obvious manner. During turning movement of the drum 17 in the manner stated, drum 18 is to be controlled by any suitable means so as to permit the bucket 16 to be held in an elevated position while traveling 45 from one to the opposite end of the supporting cable 7. When an operation similar to that above outlined has taken place, a winding of the operating cable 14 associated with the bucket 16 will cause said bucket 50 to return to its original position above the deck of the vessel 1 and the bucket 15 to return to its original position above the deck of the vessel 2. This operation is continued until a sufficient amount of coal has 55 been transferred from one to the other of the vessels.

From the foregoing, taken in connection with the accompanying drawings it is evident that the vessels may move, one relatively to the other, without causing the supporting cable 7 to snap or break; that movement of one of the supporting cables

7 cannot take place without causing the other of the said supporting cables to move in a direction opposite or counter thereto; 65 and that each bucket is dumped automatically through lowering movement in the manner aforesaid.

In reduction to practice, I have found that the form of my invention, illustrated 70 in the drawings and referred to in the above description, as the preferred embodiment, is the most efficient and practical; yet realizing that the conditions concurrent with the adoption of my device will necessarily 75 vary, I desire to emphasize the fact that various minor changes in details of construction, proportion and arrangement of parts may be resorted to, when required, without sacrificing any of the advantages 80 of my invention, as defined in the appended claim.

Having thus fully described my invention, what I claim as new and desire to secure by Letters Patent, is:—

85

A coal transferring apparatus including masts erected upon the delivering and receiving vessels, yard arms for said masts, the yard arm of the removed vessel having a pair of spaced pulleys, parallel supporting cables extended between the yard arms and supported thereby, a traveling pulley mounted on each cable, a connecting cable secured at either end to one of the traveling pulleys and passing over the yard arm pulleys whereby said traveling pulleys may move in opposite directions and in unison upon their supporting cables, an eye forming a part of each traveling pulley, a pair of drums mounted upon the delivering vessel, a cable for each drum passing through the eye of their respective traveling pulleys, buckets secured to the lower ends of each of said cables, a tripping cable for each bucket secured thereto, and to their corresponding pulleys, enlargements upon each of said drum cables whereby upon rotation of one drum to raise the buckets said enlargement is adapted to engage the traveling pulley, and said traveling pulley is thereby moved along the supporting cable in either direction as the case may be, thereby resulting in a movement of the other pulley in the opposite direction, said buckets when lowered being adapted to be 110 inverted, and their contents ejected by tightening of the trip cable.

In testimony whereof I affix my signature in presence of two witnesses.

KEN E. ROCHEL.
